John I. Williams, INVENTOR.

BY

Geo. P. Kimmel

ATTORNEY.

UNITED STATES PATENT OFFICE.

JOHN I. WILLIAMS, OF DU BOIS, PENNSYLVANIA.

FISHERMAN'S HAT.

Application filed March 8, 1926. Serial No. 93,288.

This invention relates to a hat for fishermen, and has for its object to provide, in a manner as hereinafter set forth, a fisherman's hat having means for removably connecting to the outer periphery of the crown and upper face of the brim a conveniently available supply of flies and leaders.

A further object of the invention is to provide, in a manner as hereinafter set forth, a fisherman's hat provided with means for removably connecting thereto flies and leaders in a visible and in an extended position, and further whereby a fisherman's hat, in accordance with this invention, when used will overcome the necessity of employing a leader box and further the soaking of the leaders.

A further object of the invention is to provide, in a manner as hereinafter set forth, a fisherman's hat provided with means for removably connecting thereto a number of flies and leaders in a position whereby they will be quickly dried by the sun or wind.

Further objects of the invention are to provide, in a manner as hereinafter set forth, a fisherman's hat which is simple in its construction and arrangement, strong, durable, compact, thoroughly efficient in its use, having means for expeditiously and conveniently connecting therewith, in an exposed position, a plurality of flies and leaders, and comparatively inexpensive to manufacture.

With the foregoing and other objects in view, the invention consists of the novel construction, combination and arrangement of parts, as hereinafter more specifically described, and illustrated in the accompanying drawings, wherein is shown an embodiment of the invention, but it is to be understood that changes, variations and modifications can be resorted to which fall within the scope of the claim hereunto appended.

In the drawings wherein like reference characters denote corresponding parts throughout the several views:—

Figure 1 is a side elevation of a fisherman's hat in accordance with this invention.

Figure 2 is a top plan view thereof.

Figure 3 is a section on line 3—3 of Figure 2.

Referring to the drawings in detail, 1 denotes the crown and 2 the brim of the hat and which can be constructed of any suitable material, preferably felt of the desired

thickness and rigidity so that the crown will remain in an upstanding position relative to the rim or brim and further so that the latter will not sag downwardly relative to the crown. As illustrated the crown is provided with a band 3 which surrounds the lower portion of the outer periphery of the crown, but it is to be understood that the band 3 can be dispensed with if desired. Preferably the hat is constructed with the band 3.

The outer periphery of the crown is formed with sets of vertically extending parallel rows of attaching loops, which are disposed at the front, rear and at each side of the crown. Each sets of rows of attaching loops consists of four in number and which are generally indicated at 4, 5, 6 and 7. The loops of each row of a set are indicated at 8 and are spaced from each other. The loops 8 of the rows of a set are arranged in parallelism. The loops of each row are formed from a single length of a corrugated, enameled silk vertically disposed thread 9 of appropriate thickness, which is secured to the crown in a manner to alternately oppose the inner and outer faces thereof, but the portions of the thread, which oppose the outer face of the crown and form the loops 8 are of greater length than the portions which oppose the inner face of the crown. Each row of loops extend from the upper face of the rim or brim 2, to the top of the crown, and when the band 3 is employed, the thread 8 extends therethrough as well as through the crown. The ends of the thread are anchored against the inner face of the crown as at 10, 11. The row of loops 5 is positioned centrally with respect to the rows of loops 4 and 6 and the row of loops 7 is positioned in proximity to the row of loops 6. The distance between the rows of loops 6 and 7 is materially less than the distance between the loops 5 and 6 or 4 and 5.

The upper face of the rim or brim 2 is formed with set of transversely extending parallel rows of attaching loops which are disposed at the front, rear and at each side of the brim. Each set of rows of attaching loops carried by the rim or brim 2 consists of four rows generally indicated at 12, 13, 14 and 15. The rows of the sets carried by the rim or brim 2 are of less length than the width of the latter, but the rows of each set

are arranged in the same manner as the rows of each set carried by the crown 1. The loops of each row formed on the upper face of the rim or brim 2 are indicated at 16 and each row of loops is formed from a corrugated, enameled, transversely extending silk thread 17 and which is connected to the rim or brim 2 in the same manner as the thread 9 is connected to the crown 1. The ends of the thread 17 are anchored against the lower face of the rim or brim 2 as at 18. Each set of rows of attaching loops carried by the rim or brim 2 is disposed at right angles with respect to a set carried by the crown 1.

A fly is indicated at 19 and a leader at 20. The leaders 20 are arranged on that portion of the crown which is provided with the band 3 or that portion of the crown where the band is to be positioned. The flies 19 are connected to each set of attaching loops above the band 3 and to each set of attaching loops carried by the brim. The hook 21 of the fly is inserted through the loop of a row of a set, and which loop is arranged in a row 4, the coupling portion or leader 22 for the hook is extended through the loops of the rows 5, 6 and 7 which oppose the loops of the row 4 to which the hook is attached and the loop 23 of the coupling portion or leader 22 is arranged exteriorly of the row 7 and owing to the manner in which the fly is connected to the loops of the set, the fly is maintained in an extended position and detachably connected to the crown of the hat, as well as being visible, and further positioned so that it can be dried by the sun or wind. The leader 20 is extended entirely around the crown and through the loops of the several sets and at the ends thereof overlap and which maintains the leader 20 in an extended position, as well as being visible, and further in a position to be dried by the sun or wind, and whereby it can be conveniently removed when it is desired for use. When connecting a fly to the rim or brim 2, the hook is attached to a loop of a row 12, and the coupling portion or leader thereof is extended through a loop of the row 13 and then through loops of the rows 14 and 15 and the loop portion of the leader 22 is ar-

ranged exteriorly of the row 15 and by this arrangement the fly is maintained in an extended position upon the upper face of the brim and is visible and can be readily removed when it is desired for use. Furthermore when the flies are connected to the rim or brim 2 they are maintained in a position to be dried by the sun or wind.

Although a fisherman's hat, in accordance with this invention, is designed primarily for connecting to the outer periphery of the crown and brim thereof a conveniently available supply of flies and leaders, yet it is to be understood that it can be employed for detachably connecting therewith any character of fishing appliance for which it is found applicable, particularly snelled bait hooks, by inserting same as flies, and continuing leader part of bait hook into an adjacent group of loops, due to its greater length.

It is thought the many advantages of a fisherman's hat, in accordance with this invention, can be readily understood, and although the preferred embodiment of the invention is as illustrated and described, yet it is to be understood that changes in the details of construction can be had which will fall within the scope of the invention as claimed.

What I claim is:

A fisherman's hat comprising in combination a hat body, a series of spaced, substantially parallel flexible members each having spaced portions thereof extending through said body, spaced portions thereof arranged against one face of said body and spaced portions thereof extended from the other face of said body to form loops, the loops of one member arranged in alignment with the loops of an adjacent member to provide a series of spaced sets of spaced, parallel loops, each set providing means for detachably connecting a fly or leader to the hat body, and means at the ends of each of said members for securing the member to the hat body.

In testimony whereof, I affix my signature hereto.

JOHN I. WILLIAMS.
